UNITED STATES PATENT OFFICE.

WILLIAM ROBERTSON, OF DETROIT, MICHIGAN, ASSIGNOR TO NORTHERN ENGINEERING WORKS, OF DETROIT, MICHIGAN, A CORPORATION OF MICHIGAN.

TROLLEY.

Application filed November 6, 1924. Serial No. 748,298.

To all whom it may concern:

Be it known that I, WILLIAM ROBERTSON, a citizen of the United States of America, residing at Detroit, in the State of Michigan, and county of Wayne, have invented certain new and useful Improvements in Trolleys, of which the following is a specification, reference being had therein to the accompanying drawings.

10 The invention relates to trolleys and has among its objects to provide a trolley of simple and strong construction capable of being manufactured at a low cost. Another object is to provide a method of manufacturing trolleys which will involve a minimum number of steps. A further object is to provide a trolley constructed of a unitary casting having the gear and wheel bearing centers lying in a common plane with 20 certain of the bores in alignment. A further object is to provide a trolley of compact design affording low head room with all the working parts positioned above the bridge rails.

25 With these and other objects in view, the invention resides in the novel features of construction and combinations and arrangements of parts as more fully hereinafter described and claimed.

30 Referring to the drawings which are made a part hereof and in which similar reference characters indicate corresponding parts,

Fig. 1 is a plan view showing the unitary frame construction of the trolley, the gear case covers being removed;

Fig. 2 is a front elevation of the trolley;

Fig. 3 is an end elevation of the trolley;

Fig. 4 is a bottom plan view of the caps for one of the gear casings;

40 Fig. 5 is a bottom plan view of the tap for the other gear casing, and

Fig. 6 is a bottom plan view of one of the bearing caps for the trolley wheel shaft bearings.

45 In the drawings, reference character 10 indicates the main frame of the trolley. Integrally cast with the main frame are the end gear casings 11 and 12 respectively. The frame 10 is also provided with the projection 13 forming a support for motor 14, and the projections 15, 15' forming bearings 16 and 16' for trolley wheels 17 and 17' respectively. Motor 18 is supported on the base 19 integrally cast with the main frame.

55 The gear casings 11 and 12 are provided

with upper surfaces 20 and 21 respectively lying in a common plane. The gear casing 11 is provided with semi-circular bearing portions 22, 23, 24, 25, 26 and 27. These bearing portions accommodate gear shafts 60 carrying gears as shown, for transferring energy from the motor 18 to the shaft 28 geared at 34, 35 with a drum 33.

Gear casing 12 is provided with semi-circular bearing portions 29, 30, 31, and 32 65 accommodating gear shafts carrying gears for transferring energy from the motor 14 to a shaft 36. The drum 33 is loosely mounted on shaft 36, trolley wheels 37, 37' being keyed to shaft 36, whereby the trolley is 70 driven along the bridge rails A supporting the trolley wheels 17, 17' and 37, 37'.

Bearing caps 16^a (Fig. 6) are adapted to be bolted to the complementary bearings 16' and 16 for the trolley wheel shafts 16'. 75

The centers of the bearing portions of the gear casings 11 and 12 and the trolley wheels are adapted to lie in a common plane, bearings 27 and 32 being co-axial. Bearings 26, 31; 25, 30; 24, 29; and 22, 16, 80 are also respectively aligned whereby the aligned bearings of the gear casing openings are provided in the webs of the main frame 10 when needed to accommodate the travel of the tool in boring the aligned bearings in a single operation. Proper relationship between all of the bearings is maintained as the gear casings are integrally cast with the main frame 10. The surfaces 20, 21 of the gear casings are cast in the 90 same plane whereby both of these surfaces may be machined in one operation without changing the adjustment of the tool or casting. Such machining insures exact alignment of the bearings and proper contact and relationship of the gears and trolley wheels. Likewise, bearings 27, 32, 16 and 16' lie in the plane of the surfaces 20, 21 of the gear casings in order to facilitate machining and obtain the aforesaid advantages of alignment of the bearings. 95

A cap 38 is provided for the gear casing 11, the cap having semi-circular bearing portions corresponding to those of the gear casing. The surface 39 of the cap is adapted to contact with the surface 20 of the gear casing and the parts bolted together as at 40.

Cap 41 is likewise provided with semi-circular bearing portions corresponding to 100

110

those of the gear casing 12 to which it is bolted, the surface 42 of the cap contacting with the surface 21 of the gear casing 12.

Sheaves 43 receive the hoisting cables from drum 33 in the usual manner.

It will be noted that the trolley embodying the foregoing features of my invention affords a very rigid structure, easily machined and readily assembled. Accurate alignment of all shafts is maintained by reason of the unitary structure and a reduced number of steps is involved in the manufacture of the trolley by reason of the aligned bores of the gear casings and trolley wheels having their surfaces lying in a common plane. A further advantage derived from the invention resides in the manner in which the various shafts are located in a common plane thereby affording unusually low head room permitting location of the trolley close to a ceiling. All of the gears and shafts are also readily accessible for inspection or repair from above the trolley.

While it is believed that from the foregoing description the nature and advantages of my invention will be readily understood, I desire to have it understood that I do not limit myself to what is herein shown and described and that such changes may be resorted to when desired as fall within the scope of the claims.

What I claim as my invention is:

1. In a trolley, a unitary casting comprising a main frame and a gear casing at opposite ends thereof, and a removable cap for each of said gear casings.

2. In a trolley, a unitary casting comprising a main frame and a gear casing, said gear casing having a plurality of bearing portions having their axes lying in a common plane.

3. In a trolley, a unitary casting comprising a main frame and gear casings at opposite ends thereof; the upper surfaces of said gear casings lying in a common plane, said gear casings having a plurality of bearing portions having their axes lying in a common plane.

4. In a trolley, a unitary casting comprising a main frame and gear casings at opposite ends thereof, the upper surfaces of said gear casings lying in a common plane, said gear casings having a plurality of bearing portions having their axes lying in a common plane, some of the bearing portions of one of the gear casings being aligned with those of the other gear casing whereby they may be bored in a single operation.

5. In a trolley, a unitary casting comprising a main frame and gear casings at opposite ends thereof, the upper surfaces of said gear casings lying in a common plane, said gear casings having a plurality of bearing portions having their axes lying in a common plane, some of the bearing portions of

one of the gear casings being aligned with those of the other gear casing whereby they may be bored in a single operation, and a removable cap for each of said gear casings having bearing portions complementary to those of the gear casings respectively.

6. In a trolley, a unitary casting comprising a main frame and gear casings at opposite ends thereof, the upper surfaces of the gear casings lying in a common plane.

7. In a trolley, a unitary casting comprising a main frame and gear casings at opposite ends thereof, the upper surfaces of the gear casings lying in a common plane and a removable cap for each of said gear casings.

8. In a trolley, a unitary casting comprising a main frame a gear casing presenting a horizontal surface and a plurality of trolley wheel bearing portions having their axes lying in substantially a common plane with the said horizontal surface of the gear casing to afford low head room for the trolley.

9. In a trolley, a unitary casting comprising a main frame, gear casings at opposite ends thereof, and a plurality of trolley wheel bearing portions, the upper surfaces of said gear casings and bearing portions lying in a common plane.

10. In a trolley, a plurality of trolley wheels mounted on trolley wheel shafts adapted to support the trolley, a unitary casting comprising a main frame provided with bearing portions adapted to receive said shafts, some of the bearing portions being aligned to permit boring in a single operation.

11. In a trolley, a plurality of trolley wheels mounted on trolley wheel shafts adapted to support the trolley, a unitary casting comprising a main frame provided with bearing portions adapted to receive said shafts, said bearing portions having their upper surfaces lying in a common plane, some of the bearing portions being aligned to permit boring in a single operation.

12. In combination with a pair of bridge rails, a trolley provided with a plurality of wheels adapted to traverse said bridge rails, a prime mover carried by the trolley, gearing actuated by said prime mover and bearings for mounting said gears, said bearings lying substantially in the same plane horizontally as that including the axes of the said wheels to afford low head room for the trolley.

13. In combination with a pair of bridge rails, a trolley provided with a plurality of wheels adapted to traverse said bridge rails, a prime mover carried by the trolley, gearing actuated by said prime mover and bearings for mounting said gears, said bearings lying substantially in the same plane horizontally as that including the axes of the

said wheels to afford low head room for the trolley, all of said gearing being positioned higher than the said bridge rails.

14. In combination with a pair of bridge rails, a trolley adapted to traverse said bridge rails, a prime mover carried by the trolley, gearing actuated by the said prime mover and bearings for mounting said gears, said bearings lying substantially in the same

plane horizontally whereby all of the gears 10 of the trolley are positioned with their axes lying substantially in a horizontal plane, above the bridge rails for affording low head room for the trolley.

In testimony whereof I affix my signature.

WILLIAM ROBERTSON.
